3,133,588 FORMABLE GAS BURNER

Philip M. Pappas, 2318 Blue Bonnet, Houston, Tex.
Filed Feb. 15, 1960, Ser. No. 3,761
4 Claims. (Cl. 158—99)

This invention relates to an atmospheric type of gas burner. This type of burner employs a venturi mixer before the entrance to the burner where primary air is mixed as the jet of gas emitting from a small hole or orifice 10 draws air through openings in the face of the mixer and the gas is mixed with said air and enters into the burner and emits from the burner holes or ports where it is ignited. This type of burner is very adaptable to utilize the various types of gases such as manufactured gas, mixed 15 gas and liquefied petroleum gases. In burning such gases only a change in orifice size and primary air opening is required to support good combustion. Atmospheric burners are used in ranges, water heaters, ovens, broilers, furnaces, heaters and many other appliances. In these uses they are generally supplied of cast iron construction with drilled or slotted burner ports. While said cast iron burners are relatively inexpensive and durable in their raw form, they are expensive to drill and machine as the round or slotted burner ports cannot be cast to the tolerance required at reasonable costs and hence same must be machined or drilled after the casting is completed. Further, said cast burners are necessarily of fixed size and configuration and necessary pattern equipment to cast such 20 burners is expensive. In addition, a set of said pattern equipment is required for each different shape or size and capacity of burner. A further limitation of cast burners is their heavy weight as the walls of such castings must be a minimum of approximately $\frac{3}{16}$ -inch thickness in order to prevent blow-outs and losses in the casting process. The resulting heavy cast iron burners require extra heavy and rigid mountings and supports built into the appliance in which they are used to prevent 25 damage to said appliance during transit as burners have been found to have a hammering action in transit by truck or rail and unless securely and rigidly mounted the hammering action will cause damage to the appliance. The heavy weight of the burners and their associated support structure also increase transportation costs.

Further, electric strip type of heaters have long had considerable advantage over gas heating in many applications because the electric strip heaters have flexibility, light weight, comparatively low cost plus easy and simple installation. This versatility and adaptability of electric strip type heaters has caused them to be utilized in many areas for many heating applications even though the energy cost of operating prevailing in said areas may be considerably higher than gas heating fuel costs to accomplish the same job.

With these factors in mind, I have invented a new type of atmospheric gas burner which is flexible, light weight, long lasting and requires no expensive machining, no expensive pattern equipment for each different size or configuration, nor does it require heavy rigid mountings and associated structure. Further, my light weight, flexible burner will be furnished appliance makers, gas companies and others who have use for burners in a continuous roll coil form or in long lengths so that the user may cut whatever length of burner he may need to perform a given function and may then easily coil it into a spiral form, or form it into a rectangular or square form, or a serpentine form, or make whatever form suits his purpose best and easily install it as the strip type of gas burner I have invented will also be supplied with an associated air mixer venturi to insert and attach to the entranceway of the burner section as well as an associated rear plug to close

2

the end of the burner and with associated clamps to attach said air mixer venturi and said rear plug to said strip burner. Also, suitable associated mounting supports will be furnished with the coiled or long lengths of the strip burner.

These and other objects are effected by the invention as will be apparent from the following description and claims in connection with accompanying drawings forming a part of this application in which:

In the drawings:

FIGURE 1 is a top plan view of a square shaped strip burner of my invention.

FIGURE 2 is a top plan view of a ring or spiral shaped strip burner of the invention.

FIGURE 3 is a top plan view of a serpentine shaped strip burner of the invention.

FIGURE 4 is a top sectional view taken along the line 4—4 of FIGURE 5.

FIGURE 5 is a front elevation of the burner section in FIGURE 4 looking along line 5—5.

FIGURE 6 is a perspective view of one-half of the clamp member.

FIGURE 7 is a perspective view of the rear insert plug of the strip burner section.

FIGURE 8 is a perspective view of the "T" type of mounting bracket utilized to support the strip section and keep same in a fixed position.

FIGURE 9 is a diagrammatic top plan view showing the method of forming the burner sections.

FIGURE 10 is an enlarged top plan view of the strip burner section.

FIGURE 11 is an enlarged front elevation of the strip section taken along the line 11—11 of FIGURE 10.

FIGURE 12 is a perspective view of a variation of the strip burner section.

Referring to the drawings in detail:

FIGURES 1, 2 and 3 show the strip burner sections and square, spiral and serpentine configurations respectively. Gas supply is provided by gas pipe 1 and same is injected through gas orifice 2 into the venturi mixer 4 with adjustable air shutter 3 controlling primary air for proper combustion. Venturi mixer 4 is slideably inserted into and clamped to the strip burner section 7 by means of two clamps 5 with associated bolts 6. End plug 8 is slideably inserted into and clamped to the ends of strip burner sections 7 by means of two clamps 5 with associated bolts 6 attaching same. It will be seen that after the primary air is mixed with the gas in venturi mixer 4 the combustible mixture passes through the strip burner section 7 and is ignited at each port or hole 23 formed in the upper portion of the strip burner sections. A burner pilot light, not shown, is provided to ignite the combustible mixture emanating from ports 23.

FIGURE 4 is a top sectional cutaway view taken along line 4—4 of FIGURE 5 showing burner orifice 2, adjustable air shutter 3, venturi mixer 4, clamp members 5 attaching venturi mixer 4 to strip burner section 7—7A by means of bolts 6 and nuts 9. End plug 8 is attached to the end of the strip burner 7—7A in a like manner by means of two clamp members 5 attached by bolts 6 and nuts 9. It should be noted that the dotted lines showing the bottom portion of the strip burner section have two vertical mating one-half round formed portions 11 and 11A in the same relative position as the formed ports at the top portion of the burner. These one-half round mating formed portions 11 and 11A and the parallel straight edges between are continuously joined together along the bottom portion of the burner.

FIGURE 5 is a front elevation taken along line 5—5 of FIGURE 4. Gas enters through hole 16 in orifice 2 which is held in place by screw 15. The injection of the

gas draws primary air through openings 12 and 13 into the venturi mixer 4. The air openings 12 and 13 are adjustable to provide for various types of gases and B.t.u. ratings by means of slideable air shutter 3 which is held in a fixed position by tightening screw 14 which is threaded to the face of venturi mixer 4.

FIGURE 6 is an enlarged perspective view of clamp member 5 showing angle flange 17 with bolt hole 18. The top and bottom vertical portions of clamp member 5 have one-half round formed portions 19 and 19A which keep said clamp members in a fixed relation with ports 23 at the top and the mating one-half round formed portions 11 and 11A at the bottom of said strip burner section, thus providing rigid attachment of venturi mixer 4 and end plug 8 to the strip burner sections.

FIGURE 7 is an enlarged perspective view of end plug member 8 showing flanges 43 provided with holes 44 which align with hole 18 of clamp members 5 of FIGURE 6. A radius'd inverted V portion 45 is provided at the top and bottom center of the end plug 8 to provide for a gas-tight slide fit of this portion of the end plug into the strip burner section. Similar radius'd inverted V's are provided on the exterior top and bottom center of venturi mixer 4 where same slide fits into the front of strip burner section as shown in FIGURE 5. These radius'd inverted V's provided on the slide fitted front air venturi mixed and on the rear slide fitted end plug insure their being gas-tight so that the combustible mixture emanates only from ports 23.

FIGURE 8 is an enlarged perspective view of mounting member 20 for the strip burner sections and same is provided with two mounting holes 21 to bolt same in place. One-half round formed portion 22 permits the lower one-half round mating portions 11 and 11a of the strip burner sections to slide into the narrow opening 46. It will be noted that several of the members 20 can be employed to mount the strip burner sections and support same in a relatively fixed position yet permit easy removal of said strip burner sections by simply lifting same upward. Americal Gas Association specifications on many appliances require easily removable burners and these support members provide for same.

FIGURE 9 shows a top diagrammatic view of the roll forming and welding machine for making and coiling the strip burner sections. The strip burner sections are made from two strips of thin gauge material, preferably stainless steel as same will not rust away nor corrode and while relatively expensive per pound the thin gauge and light weight of the burner provides for relatively inexpensive stainless steel construction. The thin gauge metal strips 28 and 28A will feed in from spools or coils 26—26A which rotate on shafts 27—27A into female roll from dies 29—29A rotating on shafts 30—30A. The male roll form dies 33—33A driven by shafts 34—34A follow the form of one-half of the strip burner section with the male protrusion 35—35A mating into the female sections 31—31A of the female roll from 29—29A, thus forming the strip burner sections 7—7A. The center portion of the roll forming dies also forms pleats 10—10A and the lower portion of the roll form dies form the lower one-half round portions 11—11A at the same time so that each side of the strip burner section is completely formed when same emits from the roll forming dies. Idler guide rollers 36—36A rotate on shafts 37—37A and guide the two formed strip burner sections into the rotating resistance welding rollers 38—38A rotating on shafts 39—39A. Said resistance welding rollers are of copper alloy to carry the welding current and the outer peripheral portions press and weld together the strip burner sections between the holes or ports 23 at the top of the burner sections and continuously weld the two strips 11—11A together at the bottom of the burner sections. The finished burner is then coiled onto spool or coil 41 driven by shaft 42. It will be noted that if straight lengths are required a long

straight run-out table will be provided rather than coil 41.

It will be seen that this roll forming and welding machine is capable of producing a continuous quantity of thin-wall, light gauge gas strip burners completely formed, welded and with the necessary ports closely spaced for maximum B.t.u. rating for foot of length and that same is accomplished with a minimum of labor, material and finished weight. It should be further noted that by merely changing the rotating forming and welding dies and substituting others on their respective rotating shafts strip burners of varying internal gas-carrying area can be supplied to meet different requirements.

FIGURE 10 shows the top view of a section of the formed and welded strip burner, the two sections 7—7A having accordion type pleats formed at 10—10A along their center portion with formed one-half round portions 24 and 25 providing round openings and ports 23 along the upper portion.

FIGURE 11 is an enlarged front view of strip burner section showing the formed accordion type pleats 10 along the center section, the formed one-half round portions 25 along the upper section and the inward formed one-half round portions 11 along the lower section. Although these lower one-half round formed portions 11 do not form parts or openings as the opoosing side of the strip burner section is formed in the same direction same are nonetheless desirable as they use approximately the same amount of the strip material per foot of finished burner section as the openings or ports 23 along the upper section and this prevents the strip material from wanting to climb or bend upward when it is being formed. Also, the accordion pleats 10—10A help in utilizing approximately the same amount of the strip material per foot of finished strip burner section thus further aiding in the forming process. In addition, the formed accordion pleats add to the flexibility of the burner as same permit bending of the thin gauge strip burner sections to a tight radius without same collapsing or restricting the internal passageway in order to form various configurations of burner shapes as shown in FIGURES 1, 2 and 3 and as would be required in various types of variations.

FIGURE 12 shows a perspective view of a variation of the strip burner section. This variation would provide ports or holes 23 emanating from both the upper and lower portions of the strip burner section as one-half round formed portions 24 and 25 would be formed in opposite directions at both the upper and lower edges of the burner sections. Strip burner sections of this type could be utilized in clothes dryers, for example, as said burner could be easily formed to encircle the drier drum and provide uniform heat completely around same.

I claim:

1. A gas burner comprising a substantially rectangular shaped passageway, said passageway being formed along its entire length from two thin strips of metal having their central portions formed with lateral longitudinally extending recesses and having laterally extending edges and of a length dependent only upon the length of said metal strips with each strip forming substantially half of said passageway, said two strips with both their edge portions continuously flanged outward from said passageway, said flanged edges being joined together along their lengths and provided with a plurality of half round depressions extending perpendicularly from said flanged edges and from their outer edges, said depressions on at least one side of said burner cooperating to thereby provide tubular exits from said passageway, said strips being formed along their lengths with spaced transverse inwardly pressed corrugated portions, said passageway adapted to provide varying lengths of gas burners with gas venturi mixer means affixed at one end and rear closure means provided at the other end of said burner section.

2. A gas burner as in claim 1 with said tubular exits from said passageway on both sides of said burner section.

3. A gas burner as in claim 1 with said transverse inwardly pressed corrugations thereby providing sufficient flexibility for hand bending of said burner sections into different shapes or configurations.

4. A gas burner as in claim 1 with one of said strips having one of said flanged edges formed with a plurality of half round protrusions extending perpendicularly from said flanged edges and from their outer edges, said protrusions cooperating on the other side of said burner with said depressions of said flanged edge of said opposed strip.
